UNITED STATES PATENT OFFICE.

WILLIAM C. WOODINGS, OF VERONA, PENNSYLVANIA, ASSIGNOR TO VERONA TOOL WORKS, OF PITTSBURGH, PENNSYLVANIA, A CORPORATION OF PENNSYLVANIA.

JACK.

Application filed December 18, 1922. Serial No. 681,370.

To all whom it may concern:

Be it known that I, WILLIAM C. WOODINGS, a citizen of the United States, residing at Verona, county of Allegheny, and State 5 of Pennsylvania, have invented a new and useful Improvement in Jacks, of which the following is a full, clear, and exact description.

The present invention relates broadly to 10 jacks and more particularly to improvements therein for the purpose of minimizing wear and friction between the frame and the lifting bar, for increasing the length of life of the jack, and decreasing the required 15 power for operating the same.

It has heretofore been proposed in the art to which this invention relates to provide anti-friction means between the lifting bar and the frame, in order to decrease friction 20 therebetween during the operation of the jack. In the constructions heretofore used, however, the anti-friction balls or rollers have usually been mounted loosely in a pocket in the frame of the jack. When the 25 lifting bar was operated, the balls or rollers, being loosely mounted, all tended to move towards one end of the pocket and to jam against each other. The rubbing action between the balls or rollers and between the 30 same and the lifting bar was such as to wear flat surfaces on the anti-friction members and cause them to eventually lose their ability to rotate. The anti-friction members thereafter simply acted as a single stationary friction means between the bar and the frame. In other words, the anti-friction members then functioned to increase the 35 friction between the bar and the frame instead of acting to decrease the friction therebetween. Anti-friction rollers have 40 also been employed to rotate about fixed axes, these fixed axes being provided by pins or trunnions journaled at their ends in the frame of the jack. This manner of mounting the rollers not only increases the cost of 45 construction, but also increases the difficulty of assembling the parts.

By the present invention, I propose to 50 mount the anti-friction rollers for rotation about fixed axes, but to avoid the objection to rollers as heretofore mounted in this manner by providing open bearings for the rollers preferably formed in means removably mounted in a pocket in the frame of the

jack. This construction enables the rollers 55 to be readily placed in the bearings and the assembled rollers and bearings to be easily mounted in the frame.

In the accompanying drawings, which illustrate a preferred embodiment of my invention, 60

Figure 1 is a side elevation, partly broken away, illustrating a jack having my improved anti-friction means incorporated 65 therein; and

Figure 2 is a detail view of the anti-friction rollers and the removable bearings for the same.

The present invention is not limited in its range of usefulness to any particular form 70 of jack, but is adapted for use in jacks comprising a frame member and a lifting bar between which there is a relative movement axially of the bar. In the construction illustrated, there is provided a frame 75 2 having an opening 3 extending longitudinally therethrough and in which is located a lifting bar 4. The lifting bar is formed with a series of teeth 5 providing an operating rack and is provided with both 80 a lifting foot 6 and a lifting head 7. As is customary in the art, the frame is provided with a pivotal mounting 8 for an operating handle 9 which extends beyond the opposite 85 sides of its pivotal mounting. On its inner end the handle carries a pivotally mounted lifting pawl 10, which is adapted to engage the teeth 5 on the lifting bar for raising the bar as the outer end of the handle is swung 90 downwardly. The bar is held in its elevated position during the return movement of the operating handle by a holding pawl 11.

During operation of the jack, it will be apparent that the lifting pawl 10 tends to force the lifting bar away from the pivotal 95 axis of the pawl and into engagement with the rear portion of the frame. In order to minimize to as great an extent as possible the resulting friction, anti-friction rollers 12 are arranged in a pocket 13 in the frame. These anti-friction rollers engage the rear edge 100 of the lifting bar and prevent the same from coming into frictional engagement with the rear portion of the frame. The rollers 12 are journaled in open bearings formed in a 105 U-shaped member 14. This U-shaped member 14 is of approximately the same width and length as the corresponding dimensions

of the pocket 13, so that the U-shaped member is adapted to fit snugly in said pocket.

It will be apparent that the U-shaped member 14 maintains the rollers in fixed spaced relationship and that the construction is such as to enable the rollers to be quickly mounted in said bearings and the bearings readily assembled in the pocket in the jack. While I have shown the bearings as formed in a U-shaped member, it will be understood that the invention is not limited to this particular form of construction, but may be otherwise embodied within the scope of the appended claims.

I claim:

1. In a jack, a frame, a lifting bar slideable therein, and an anti-friction roller effective intermediate the frame and the lifting bar for maintaining the bar out of direct sliding contact with the frame, said roller being mounted in removable bearings held in position by said lifting bar, substantially as described.

2. In a jack, a frame, a lifting bar, and a plurality of anti-friction rollers effective intermediate the frame and the lifting bar for maintaining the bar out of direct sliding engagement with the frame, said rollers being mounted in bearings which maintain them in fixed relationship, said bearings being formed in a removable member which is held in position by said lifting bar, substantially as described.

3. In a jack, a frame, a lifting bar, and a

plurality of spaced anti-friction rollers arranged in a pocket in the frame for maintaining the bar out of direct sliding engagement with the frame, said rollers being mounted in bearings formed in a member which is held in said pocket by said lifting bar, substantially as described.

4. In a jack, a frame, a lifting bar, and a plurality of spaced anti-friction rollers arranged in a pocket in said frame for maintaining the bar out of direct sliding engagement with the frame, said rollers being mounted in removable open bearings formed in a member positioned in said pocket, said rollers being held in said bearings by said lifting bar, substantially as described.

5. In a jack, a frame, a lifting bar, and a plurality of spaced anti-friction rollers arranged in a pocket in said frame for maintaining the bar out of direct sliding engagement with the frame, said rollers being mounted in open bearings formed in a U-shaped member removably seated in said pocket, substantially as described.

6. In a jack, a frame, a lifting bar slideable in said frame, and an anti-friction roller effective intermediate the frame and the lifting bar for maintaining the bar out of direct sliding contact with the frame, said roller being mounted in open bearings and held in position thereby said lifting bar, substantially as described.

In testimony whereof I have hereunto set my hand.

WILLIAM C. WOODINGS.
